UNITED STATES PATENT OFFICE.

ALFRED G. F. KUROWSKI, OF BROOKLYN, NEW YORK, ASSIGNOR TO UNDERWOOD TYPEWRITER COMPANY, OF NEW YORK, N. Y., A CORPORATION OF DELAWARE.

TYPEWRITING MACHINE.

Application filed October 26, 1923. Serial No. 670,826.

The invention relates to means for holding and manipulating stencil backings, such, for instance, as celluloid, on the platen of a typewriting machine.

Such backings are set upon or over the platen to provide a hard or unyielding surface against which to cut the stencil. The stencil-cards, because they have margins of card-board or relatively rigid and unbendable material, are usually set in special holders which are line-spaceable with the cards over the surface of the platen. Preferably the platen, itself, is not line-spaced in the writing of a stencil. Where considerable stenciling work is to be done, it is convenient to employ a platen having the backing piece fixed thereon, instead of on the card-holder. Heretofore, however, unless platens, having the backing fixed thereto, have had line-space movement with the card-holder, the typing has always been at one line-position on the backing piece; with the result that the backing piece has soon become worn and has had to be replaced or reversed.

The object of the present invention is the provision of means whereby, in a machine in which the platen has no line-space movement in stenciling, and in which the backing is fixed to the platen, the backing may nevertheless be typed upon over substantially its entire area.

More particularly, a feature of the invention is the provision of means for effecting a rotary adjustment of the platen with the backing, after the latter is worn at one line-position thereof, so that successive line-positions of the backing may be set for impact of the type thereon.

A feature of the invention is a gage for determining the successive settings or adjustments of the platen and backing, and for indicating, at all times, the existing adjustment of the backing, and the amount of worn and fresh area of the backing.

Other features and advantages will hereinafter appear.

In the accompanying drawings,

Figure 1 is a front view of a platen and associated parts embodying the present invention.

Figure 2 is an end view, taken on the line 2-2 of Figure 1, and showing a type-bar in striking position.

Figure 3 is a perspective view of the

right-hand end of the platen, showing more particularly the gage, and mounting therefor, for effecting the desired rotary setting of the platen and celluloid.

The platen 10 has end pieces 11 with hubs 12 thereon, so that, by means of set-screws 13, the platen may be fixedly secured to a shaft 14, journaled in the end plates 15 of the platen carriage or frame. Upon loosening the screws 13, the shaft 14 may be withdrawn lengthwise from the platen and the platen removed from the machine. This enables the special platen 10 shown in the drawings to be substituted in the machine for the ordinary platen used in other work.

For line-spacing the ordinary platen there is a ratchet-wheel 16 fast to the platen axle, which is rotated by any suitable line-space mechanism, such, for instance, as that commonly found in the standard Underwood typewriting machine, and which comprises a slide (not shown) carrying a pawl (not shown) for engagement with the ratchet-wheel. A spring detent 17 by engagement with the ratchet-wheel, in the standard machine, holds the platen in line-spaced position against accidental rotary displacement. The axle 14 of the present special platen is also equipped with this ratchet-wheel 16 and detent 17; but, as hereinafter pointed out, the ratchet-wheel 16 and detent 17 here are employed simply to hold the platen in its setting, against accidental rotary displacement. The axle 14 of the present special platen is also provided with the usual hand-wheels 18, whereby the platen may be rotated when desired.

Stencil-cards, one of which is shown in the machine at 19, are successively placed in a card-holder 20, which latter is not mounted in a suitable manner for line-space movement with the card over the surface of the platen while the latter is held against rotation by the detent 17. The card-holder may be mounted, by means not shown, on a shaft 21 on a card-holding frame 22 detachably secured by screws 23 to the side pieces 15 of the platen-frame.

The mounting of the card-holder, and the means by which it receives its line-space movement with the card, are like that shown in my co-pending application, Serial No. 666,907, filed October 6, 1923, to which reference is made to such understanding thereof as may be necessary. In my aforesaid co-

pending application, line-space mechanism for the card-holder is actuated by connections to the usual platen line-space mechanism, at a time when the latter is inoperative upon the platen. In that application, I showed the clutch device set forth in United States Letters Patent to Helmond, No. 1,150,866, dated August 17, 1915, as the means whereby the line-space mechanism 5 might be rendered ineffective to line-space the platen while nevertheless remaining effective to line-space the card-holder. In the present structure such clutch mechanism is omitted; and the usual line-space mechanism is rendered ineffective, to line-space the platen, by removal of the pawl which ordinarily co-operates with the ratchet-wheel 16; the line-space mechanism remaining effective, however, to line-space the card-holder by virtue of the connections shown 10 in my aforesaid co-pending application.

A backing piece 24, such, for instance, as celluloid, is shown as secured to the face of the platen by means of clips 25. There is 15 a pair of these clips at each side of the card-holder frame; and the clips of each pair are opposed to each other and slightly offset from the surface of the platen, to permit the front and rear edges of the backing 20 piece or celluloid to be inserted thereunder. Screws 26 hold the clips 25 to the platen. The clips 25 are shown as set beyond the 25 side margins of the card-holder 20, so that the latter may not interfere with the placement and removal of the backing pieces.

Since the platen and backing piece are held by the detent 17 against rotary movement, while the card-holder is line-spaced successively with each card or stencil, the 30 backing piece will be repeatedly typed upon at the same line-position thereof. At such line-position of the backing piece, the same ultimately therefore becomes worn. In accordance with the present invention, when 35 such wear has reached an objectionable stage, a fresh surface of the backing piece or celluloid may be presented to the printing line. This is accomplished by turning the platen with the backing piece, as by 40 means of one of the hand-wheels 18, one or more line-space distances to a new rotary setting thereof. The detent 17 permits this 45 rotary adjustment of the platen and backing piece, and holds the platen with the 50 backing piece in the new position to which it has been turned. A fresh backing surface having been thus presented to the printing line, the writing or stenciling on the cards 55 may proceed as before until a further rotary adjustment of the platen with the backing piece becomes desirable.

In order that the wear on the backing piece may be extended progressively from the front to the rear edges thereof, and in 60 order that the line-position of typing on

the stencil may at all times be known, and in order that the proper movement of the platen with the backing piece for a new setting thereof may be properly determined, a gage is provided. This gage consists of 65 a plate 27 carried by arms 28 at the rear thereof, on the shaft 21, and being curved forward and downward as at 30 over and around the surface of the platen. This 70 plate has graduations 31 at line-space distances apart thereon along the path of rotary adjustment of the platen. These 75 graduations are preferably progressively numbered, from front to rear, as indicated at 80 32. On a plate 33 secured by screws 34 to the surface of the platen is a pointer or indicator 35 for registering with the 85 graduations 31 on the gage-plate 27.

In adjusting the platen and backing piece, the platen is turned one line-space distance 90 at a time, starting at the position in which the pointer 35 registers with the graduation numbered 1 on the plate 27, and continuing until the pointer registers with the graduation numbered 8. In the instance shown, the backing piece is of such width that 95 eight adjustments of the platen result in the use of substantially the entire surface of the backing piece. Of course, if desired, the backing piece might be made wider, and 100 further adjustments thereof provided on the gage-plate.

For holding the gage-plate 27 down in proper position over the platen and for preventing angular distortion or displacement thereof, the plate 33 is preferably provided with a stud or block 36 which projects through a slot 37 extending lengthwise of the plate 27, and which has offsets 38 105 over the upper surface of the plate.

Variations may be resorted to within the scope of the invention, and portions of the improvements may be used without others.

Having thus described my invention, I 110 claim:

1. In a typewriting machine, the combination with a rotatable platen, types, a backing piece for stencil-cutting affixed to the face of said platen and overlying a plurality of line-position zones thereof, and means for disposing said zones, one at a time, at the printing line of said machine, whereby a fresh surface of said backing piece may be presented, from time to time, for engagement with said types, of a gage 115 arranged for indicating the adjustment of said backing piece necessary for bringing a fresh surface thereof to said printing line.

2. In a typewriting machine, the combination with a platen-frame, a platen, a backing piece for stencil-cutting affixed to the face of said platen and overlying a plurality of line-position zones thereof, and means for disposing said zones, one at a time, at the printing line of said machine,

of a projecting stud-piece mounted on said platen, and a curved gage-plate mounted on said platen-frame and disposed parallel with the convex surface of said platen and 5 having a lengthwise slot arranged to engage around said stud-piece, thereby limiting the extent of the rotary movement of said backing piece away from said printing line.

10 3. In a typewriting machine, the combination with a platen-frame, a platen, a backing piece for stencil-cutting affixed to the face of said platen so as to overlie a plurality of line-position zones thereof, and 15 means for disposing any one of said zones at the printing line of said machine, of a curved gage-plate mounted on said platen-frame and disposed parallel with the convex surface of said platen and having a lengthwise slot and graduations therealong, a 20 pointer on said platen for registering with the graduations on said gage-plate, and a stud-piece mounted on said platen and engaging in said slot, thereby limiting the rotary movement of said backing piece, the 25 length of said slot being arranged so that some portion of said backing piece will always be at said printing line.

4. In a typewriting machine, a platen, a 30 backing piece, such for instance as celluloid, affixed to the face of the platen, a card-holder, means for adjusting the position of the platen to present a fresh surface of the backing piece to the printing line, and 35 a gage whereby to determine the desired adjustment of the platen and backing piece, said gage comprising a graduated plate on the platen-frame and an indicator on the platen for registering with the graduations 40 on the gage-plate.

5. In a typewriting machine, a platen, a 45 backing piece, such for instance as celluloid, affixed to the face of the platen, a card-holder, means for adjusting the position of the platen to present a fresh surface of the 50 backing piece to the printing line, and a gage whereby to determine the desired adjustment of the platen and backing piece, said gage comprising a graduated plate on the platen-frame slotted lengthwise of the path along which the platen is adjustable, an indicator on the platen for registering with the graduations on the gage-plate, and a stud or block on the platen set within the 55 slot in the gage-plate.

6. In a typewriting machine, a platen, a 60 backing piece, such for instance as celluloid, affixed to the face of the platen, a card-holder, means for adjusting the position of the platen to present a fresh surface of the 65 backing piece to the printing line, and a gage whereby to determine the desired adjustment of the platen and backing piece, said gage comprising a graduated plate on the platen-frame slotted lengthwise of the

path along which the platen is adjustable, an indicator on the platen for registering with the graduations on the gage-plate, and a stud or block on the platen set within the slot in the gage-plate and being offset over 70 the outer face of the gage-plate to hold the gage-plate in position with respect to the platen.

7. In a typewriting machine, a rotary platen, a backing piece, such for instance as 75 celluloid, affixed to the face of the platen, a card-holder, means for effecting a rotary adjustment of the platen to present a fresh surface of the backing piece to the printing line, and a gage whereby to determine the desired adjustment of the platen and backing piece, said gage comprising a graduated plate affixed to the platen-frame and curved over the surface of the platen, and an indicator on the platen for registering with the graduations on the gage-plate.

8. In a typewriting machine, a rotary platen, a backing piece, such for instance as celluloid, affixed to the face of the platen, a card-holder, means for effecting a rotary 80 adjustment of the platen to present a fresh surface of the backing piece to the printing line, a gage whereby to determine the desired adjustment of the platen and backing piece, said gage comprising a graduated plate affixed to the platen-frame and curved over the surface of the platen, and an indicator on the platen for registering with the graduations on the gage-plate, and means for holding the platen in gaged position.

9. In a typewriting machine, a rotary platen, a backing piece, such for instance as celluloid, affixed to the face of the platen, a card-holder, means for effecting a rotary 95 adjustment of the platen to present a fresh surface of the backing piece to the printing line, a gage whereby to determine the desired adjustment of the platen and backing piece, said gage comprising a graduated plate affixed to the platen-frame and curved over the surface of the platen, and an indicator on the platen for registering with the graduations on the gage-plate, and means 100 comprising a ratchet-wheel on the platen and a detent for engagement with the ratchet-wheel to hold the platen in gaged position.

10. In a typewriting machine, a platen, mechanism for line-spacing the platen, means for disabling the platen line-space mechanism, a card-holder, a backing piece, such for instance as celluloid, secured to the face of the platen, and means for adjusting the setting of the platen and backing piece, 105 to present a fresh surface of the backing piece to the printing line.

11. In a typewriting machine, a platen, a backing piece, such for instance as celluloid, affixed to the face of the platen, a card- 110

holder, means for adjusting the position of the platen to present a fresh surface of the backing piece to the printing line, and a gage whereby to determine the desired adjustment of the platen and backing piece, said gage comprising a plate having graduations thereon at line-space distances apart along the path of adjustment of the platen, and an indicator on the platen for registering with the graduations on the gage.

12. In a typewriting machine, a rotary platen, mechanism for line-spacing the platen comprising a ratchet-wheel affixed to the platen, means for disabling the platen line-space mechanism, a detent for engagement with the ratchet-wheel to hold the platen against rotary displacement while

the platen is held by the detent, a card-holder, a backing piece, such for instance as celluloid, secured to the face of the platen, 20 and means for effecting a rotary adjustment of the setting of the platen and backing piece, to present a fresh surface of the backing piece to the printing line, the adjusting means comprising a gage-plate af- 25 fixed to the platen-frame and extending over the surface of the platen and having graduations thereon at line-space distances apart along the path of adjustment of the platen, and an indicator on the platen for 30 registering with the graduations on the gage-plate.

ALFRED G. F. KUROWSKI.
